IDENTIFICATION DEVICE FOR LUGGAGE

Lester B. Coleman, New York, N. Y.

Application June 6, 1946, Serial No. 677,360

3 Claims. (Cl. 40—61)

1

The present invention relates to improvements in identification devices, and more specifically, to a new and improved identification holder for luggage, handbags, brief cases, and the like.

It is well known to attach identification tags, which bear the owner's name and address, to suitcases, trunks, or brief cases. However, these hitherto used identification devices can easily be torn off or lost, which is highly objectionable. Moreover, they display openly the name and address of the owner thus subjecting him possibly to undesired solicitations or invasions of his privacy.

Therefore, the main object of the present invention is the provision of a device of the character described which is firmly secured to and embedded into the suitcase or other object to be identified, so that it cannot be removed inadvertently regardless of to how rough a treatment said object may be subjected.

Another object of the present invention is the provision of a device of the character described which has its identification card normally covered by a lid and which is flush with the surface of the suitcase or the like and is of inconspicuous appearance, so that it—when said lid is closed—hardly can be noticed and does not appear as an identification device.

Still another object of the present invention is the provision of a device of the character described which is simple in construction, so that it can be manufactured and sold at a very reasonable price, and which is also sturdy and durable as well as easy to manipulate.

Yet a still further object of the present invention is the provision of a device of the character described which can be attached to any existing pieces of luggage or the like without substantial alterations, and which is likewise well adapted to be attached to new objects while they are being manufactured.

Further objects of the instant invention reside in any novel feature of construction or operation or novel combination of parts present in the embodiment of the invention described and shown in the accompanying drawing whether within or without the scope of the appended claims and irrespective of other specific statements as to the scope of the invention contained herein.

In the drawing:

Figure 1 is a top elevation of a suitcase which is provided with a preferred embodiment of my invention;

Figure 2 is a top plan view of a preferred embodiment of my invention as it appears before it

is attached to a suitcase or the like and being shown with its lid open and drawn in an enlarged scale:

Figure 3 is a front elevation of the embodiment of Figure 2;

Figure 4 is a cross-sectional view on the line 4—4 of Figure 2 showing the device with its lid about half open;

Figure 5 is a longitudinal sectional view on the line 5—5 of Figure 2 showing the device with its lid closed; and

Figure 6 is a side elevation of the embodiment of Figure 2.

Similar reference characters refer to similar parts throughout the several views.

In the drawing the numeral 1 denotes an entire embodiment of my invention comprising an open casing 2 of metal, plastic material, wood or the like which has a back wall, side walls and end walls which are flanged at the front, and which is adapted to be arranged in a recess in the object to be identified in such a manner that the top portion of the casing is flush with the surface of said object as indicated in Figure 4. The casing

2 is preferably rectangular, and an identification card 9 bearing the name and address of the owner is placed upon the back wall of the casing

2. In order to prevent any possible tampering with the identification card 9, I prefer to protect the same by means of a transparent plate 4, which is above the card 9 and whose edges engage grooves 3 that are provided in the end and side walls of the casing 2 (Figure 4, 5, and 6).

A lid 5, preferably consisting of the same material as the casing 2, is pivotally arranged in the upper portion of the casing 2 in such a manner that it—when closed—is flush with the outwardly flanged extremities at the front of the side and end walls of the casing 2. I prefer to carry out

this feature of my invention in the manner shown in the drawing, where it will be seen that a pin 6 is extended through the lid 5 and is in spaced relation to the latter's left longitudinal side, and both end portions of the pin 6 are extended through the end walls of the casing 2 as well as through lugs 7 (Figs. 5 and 6). When the lid 5 is closed it covers the entire otherwise visible surface of the transparent plate 4, so that the identification card 9 cannot be seen. In order

to open the lid 5, one presses slightly upon its right longitudinal edge, whereupon it will assume the position illustrated in Figure 4.

In order to prevent any protruding of my new and improved identification holder 1 (when the lid 5 is closed) over the surface of the suitcase

10, I prefer to provide said surface with a recessed portion in which rests the outwardly flanged portions of the side and end walls of the casing 2, and to extend the major portion of the latter into the suitcase 10, as shown in Figure 4. The casing 2 itself can be secured to the object 10 by any suitable means preferably by means of tongues 8 which are driven through and anchored in the wall of the object 10 (Figure 4) and which are formed as a unit with the outwardly flanged portions of the side walls of the casing 2.

In order to facilitate the insertion and the removal of the identification card 9, I prefer to provide one of the end walls of the casing 2 with a slot 20 (Figure 5), which is long and wide enough to pass the card 9 therethrough. Specifically for facilitating the removal of an identification card, for instance in case of a change in ownership of the object 10, there may also be provided another slot 21 in the opposite shorter side wall of the casing 2. This slot 21 is of such a size and is placed in such a manner that the transparent plate 4 can be pushed therethrough. This arrangement of the slots 20 and 21 makes it practically impossible to interchange identification cards 9 unless the suitcase 10 is open, so that any tampering with the identification card 9 can be prevented almost entirely by keeping the object 10 locked.

The color and outer appearance of the entire holder 1 is preferably chosen so that it will blend with the other fittings of the object 10, thus making the device highly inconspicuous. The lid 5 remains closed except when necessary to open it for positive identification.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention, what I claim as new and desire to secure by Letters Patent is:

1. An identification holder comprising an open casing adapted to be arranged in a recess in the object to be identified in such a manner that the top portion of the casing is flush with the surface of said object and having grooves in its side and end walls, an identification card resting upon the

back wall of said casing, a transparent plate resting upon said card and having its edges received in said grooves, and an opaque lid hingedly attached to the upper inside portions of the end walls of said casing.

2. A device of the character described comprising an open casing having a back wall as well as end and side walls which are flanged outwardly at the front and said end and side walls being provided with grooves at their inner sides, an identification card resting upon the back wall of said casing, a transparent plate resting upon said card and having its edges received in said grooves in the end and side walls of said casing, an opaque lid inserted in the upper portion of said casing in such a manner that it is normally flush with the outwardly flanged portions at the front and side walls, and a pin extended through said lid at some distance from its edges and through the end walls of said casing, said casing being embedded in the object to be identified in such a manner that the front of said outwardly flanged side wall is flush with the surface of said object, and at least one of said walls having a horizontal slot adapted for passing said card therethrough.

3. An identification holder comprising an open rectangular casing having a back wall and side and end walls which are provided with grooves at their inner sides and said side walls being flanged outwardly at the front, an identification card resting upon the back wall of said casing, a transparent plate resting upon said card and having its edges received in said grooves in the side and end walls of said casing, an opaque lid inserted in the upper portion of said casing in such a manner that it is normally flush with said outwardly flanged extremities of said side walls, and a pin extended through the upper portion of the end walls of said casing and through said lid and being parallel to and in spaced relation to one of the side walls of said casing, said casing being adapted to be arranged in a recess in the object to be identified in such a manner that the front portion of the casing is flush with the surface of said object, and one of the end walls having a horizontal slot adjacent said card.
